UNITED STATES PATENT OFFICE

MARTIN R. HORETH, OF BROOKLYN, NEW YORK

AEROPLANE

Application filed February 6, 1929. Serial No. 337,866.

This invention relates to aircraft of the heavier-than-air type and proposes an aeroplane construction by which the factors of safety in flight and in landing are enhanced. 5 The principal object of the invention is the provision of means, operable at will to depress the tail of the aeroplane for bringing it out of a nose dive or for moderating the steepness of a glide, as well as holding down 10 the plane when it has once established contact with the ground, upon landing.

Another object of the invention is to provide means functioning as a wind brake to bring the aeroplane quickly and smoothly to 15 a standstill.

Still another object of the invention is the provision of an auxiliary tiltable wing contributing its factor to the lifting capacity of the aeroplane as well as performing the functions indicated in the objects aforesaid. 20

Other objects of the invention will appear as the following description of a preferred embodiment thereof proceeds.

In the drawings, in which the same characters of reference are used to designate similar parts throughout the several figures,

Figure 1 is a side elevation of an aeroplane embracing the principles of the invention,

Figure 2 is a front elevation partly in section taken along the line 2--2 of Figure 1,

Figure 3 is a vertical longitudinal section, the front and rear-most portions of the plane being omitted,

Figure 4 is a front elevation on an enlarged scale showing details of the control gears,

Figure 5 is a diagrammatic illustration indicating how an aeroplane is brought out of a nose dive with the aid of the present invention.

Referring now in detail to the several figures, the numeral 1 represents the body or fuselage of the aeroplane, 2 being the cockpit or cabin, and the main or sustaining wing being indicated by the numeral 3. Disregarding the additional structure embodying

the present invention, this would be an aeroplane of the monoplane type although the invention is equally applicable to a biplane.

The invention comprises an auxiliary wing 4 positioned above the main wing 3 and pivotally mounted adjacent its ends on fixed standards 5 erected adjacent the forward edge of the main wing and suitably braced. The width of the auxiliary wing from front to rear is preferably such that the rearward edge of the auxiliary wing terminates slightly forward of the rearward edge of the main wing. The auxiliary wing 4 is oscillatable about its pivotal connection through a range of positions extending between its normal position as shown in full lines in Figure 3 and the broken line position indicated at 4' in which the rear edge of the auxiliary wing is contiguous to but is spaced from the rear edge of the main wing to cooperate therewith in the formation of a restricted opening or slot for the passage of air.

In further alluding to this feature of the invention, attention is invited to Figure 3 in which it is illustrated that when the wing 4 is adjusted to the dotted line position shown at 4', the air encountered will be deflected downwardly into pressure contact with the rear edge portion of the main sustaining wing and will depress such portion of the main wing with the result that the plane is nosed up and is brought into the gentle glide suggested in Figure 5.

Particular attention is invited to the fact that the standards 5 are mounted adjacent the upward edge of the main sustaining wing 3 so that simultaneously with the depression of the rear edge portion of the main wing, a lifting force will be applied to the forward edge of the main wing.

Of course, in carrying out the invention, the standards 5 and the bracing means therefor are positioned to allow of the free and normal oscillation of the ailerons in response to the adjustment thereof by the pilot.

Means for adjustably positioning and holding the auxiliary wing in any one of its positions is shown, particularly in Figures 1 and 3, comprising sectors 7 secured to the auxiliary wing at its rear portion and concentric with its pivotal connection. Said sectors preferably pass through and terminate below suitable slots 8 formed in the main wing and are provided with teeth 9 intermeshing with the teeth of the pinions 11 carried by the shaft 12 which extends transversely of the aeroplane. Said shaft is operated from a worm and worm wheel drive 13 by means of a chain 14 passing over suitable sprockets 15 and 16 operatively connected, respectively, to the worm drive and to the shaft 12.

It will be understood that the specific operating means as shown is merely by way of example and that any other equivalent operating means might be substituted therefor without transcending the scope of the invention. The worm and sector drive is operated by a suitable handle 17.

The sectors 7 as well as the standards 5 are designed to act as struts supporting the auxiliary wing in any position of adjustment of the latter and in this regard it will be noted that the worm and sector drive is irreversible, so that the portion of the sustaining load borne by the auxiliary wing is rigidly sustained by the driving mechanism without imposing any stress upon the operating handle which may be left free after adjustment of the auxiliary wing has been made.

With the auxiliary wing in the position shown at 4' in Figure 3 the air current striking the lower surface of said wing is deflected downward as indicated by the arrows striking the main wing near its rear portion, that is to say, to the rear of the center of mass of the aeroplane, exercising a turning moment upon the aeroplane about some exterior point such as 18 lying in a vertical line passing through the center mass of the aeroplane. This, of course, tends to depress the tail of the aeroplane, which function is particularly useful in bringing a plane out of a nose dive as indicated in the three positions *a*, *b*, *c*, successively shown in Figure 5.

This auxiliary control is, also, of the greatest advantage in moderating the steepness of a glide, by tending to elevate the nose of the aeroplane, thus taking considerable of the strain off of the horizontal rudder. In exercising this control, the position of the pivotal connection of the auxiliary wing is as far forward of the center of mass of the aeroplane as is practicable, increases the leverage of the auxiliary wing and producing the maximum of depressing force upon the tail of the aeroplane with the minimum extent of adjustment of the auxiliary wing. This is of great importance since naturally the more the auxiliary wing is inclined the

greater will be the head resistance of the aeroplane, with consequent falling off in speed.

The depression of the tail of the aeroplane by the auxiliary wing is also advantageous in a major way when landing. Normally, when an aeroplane establishes first contact with the ground there is a tendency for it to kick up from the rear. This tendency may be inhibited completely by the control which the pilot is enabled to exercise, through the present invention in keeping the tail depressed.

When the auxiliary wing is adjusted to the position shown at C in Figure 5 or in a position approximately thereto, it acts as an effective brake by almost completely occluding the space between the wings and thereby offering a maximum head resistance to the wind. This is a particularly safe and efficient mode of braking since it is entirely independent of ground inequalities and is sufficiently extensive to bring the plane to a quick standstill. At the same time, its tendency is to push the aeroplane backward, stabilizing it upon its tail preventing it turning over on its nose.

It will of course be recognized that when the auxiliary wing is in its intermediate position concentrating the air current down upon the main sustaining wing, the vacuum above said main wing upon which the aeroplane ordinarily depends for much of its lifting power, is destroyed. This is, however, compensated for almost entirely by the vacuum above the auxiliary wing, and which vacuum increases, up to a certain limit, the more the auxiliary wing is tilted.

While I have in the above description endeavored to disclose what I believe to be a preferred and practical form of my invention, it is to be understood that the specific details as shown are merely by way of example and not to be considered limitative in their bearing upon the scope of the invention.

What I claim as my invention is:

1. In an aeroplane, a main sustaining wing, struts extending above said wing adjacent the forward edge thereof, an auxiliary wing pivoted adjacent the forward edge thereof to said struts, toothed sectors extending downward from the rear edge portion of said auxiliary wing, said main wing being provided with slots for the passage of said sectors, a transversely extending shaft beneath said main wing and having gears meshing with the teeth of said sectors, and means connected to said shaft to operate the same.

2. In an aeroplane, a main sustaining wing, struts extending above said wing adjacent the forward edge thereof, an auxiliary wing pivoted adjacent the forward edge thereof to said struts, toothed sectors extending downward from the rear edge portion of

said auxiliary wing, said main wing being provided with slots for the passage of said sectors, a transversely extending shaft beneath said main wing and having gears meshing with the teeth of said sectors, and control means connected to said operating shaft and embodying an intermeshing worm and worm wheel holding the auxiliary wing in adjusted position.

10 In testimony whereof I affix my signature.
